UNITED STATES PATENT OFFICE.

WILLIAM ELLK, OF PITTSBURGH, PENNSYLVANIA, ASSIGNOR OF ONE-HALF TO
JOSEPH SINKOVITZ, OF CARRICK, PENNSYLVANIA.

CRUSHING-MACHINE.

1,352,797.

Specification of Letters Patent. Patented Sept. 14, 1920.

Application filed March 26, 1919. Serial No. 285,170.

To all whom it may concern:

Be it known that I, WILLIAM ELLK, a citizen of the United States, residing at Pittsburgh, in the county of Allegheny and State of Pennsylvania, have invented new and useful Improvements in Crushing-Machines, of which the following is a full, clear, concise, and exact description, reference being had to the accompanying drawings, forming part of this specification.

My invention pertains to crushing machines, and relates especially to machines in which the material to be crushed is supplied to a rotating receiver in which it is acted upon by a plurality of spheres, rolls, or the like.

It is an object of my invention to provide a crushing machine in which the crushing action will take place evenly and effectively. 20 It is another object of my invention to produce a crushing machine having provision for reducing any over-large material which may be present after the main crushing operation has taken place. It is another 25 object of my invention to provide a crushing machine which will deliver the crushed product in a sufficiently divided form, which will be rapid in operation, and which will be of a simple and rugged construction. 30 Other and further objects of my invention will become apparent from the following specification, taken in connection with the claims appended thereto.

I have described, by way of example, in 35 the following specification, and shown in the accompanying drawings, one form of crushing machine embodying my invention. I wish it to be understood, however, that my invention may be embodied in other forms, 40 and that changes may be made in the particular form described and shown, without exceeding the scope thereof, as defined in the appended claims.

In the drawings: 45 Figure 1 is a plan, partly in section, of a crushing machine constructed in accordance with my invention; and

Fig. 2 is a sectional elevation of the same, the section being taken on the line 2—2 of 50 Fig. 1, looking in the direction of the arrows.

Like reference characters refer to like parts throughout the following specification and the figures of the drawings.

Referring now to the drawings, 10 indi-

cates a foundation in which is embedded a 55 thrust bearing 11, which receives a stem 12. The foundation also carries a circular track 13 in which are mounted rotary track rollers 14. Rotatably mounted, by means of a bearing socket 15, upon the stem 12, is a receiver 60 into which is deposited the material to be crushed. This receiver comprises a central deflecting portion 16, and an annular channel 17. Beyond the channel 17, the receiver is formed in a conical shape, as at 18, and 65 has secured thereto a hardened conical disk 19. Beyond the conical portion 18, the receiver is formed with an outwardly extending flange carrying a ring-gear 21, to which a rotary motion is imparted by a pinion 22 70 carried by a drive shaft 23. The receiver is formed, beyond the outer edge of the conical portion 18, with a plurality of air apertures 24 for a purpose to be hereinafter described.

Supported by tie-rods 25, are a pair of bearing-rings 26 and 27, respectively, between which run rolls 28, carried by a hood member 29. This hood member is formed with a downwardly extending flange 30 having secured thereto a gear-ring 31 which engages with the pinion 22 from above. In this manner the hood member is rotated in an opposite direction to that in which the receiver turns. The hood member carries 80 a plurality of plungers 32, operated upon by springs 33, which engage, at their lower ends, with a bearing-ring 34. This bearing-ring engages downwardly upon a plurality of crushing spheres 35 which run in the 85 channel 17 of the receiver. The hood member is also provided with a plurality of plungers 36, acted upon by springs 37, which plungers carry a grinding member 38 having a conical lower surface 39 which 90 cooperates with the upper surface of the conical disk 19.

The hood member further carries bearings for a plurality of pairs of auxiliary crushing rolls, each of which pairs consists 100 of a roll 40 and a roll 41, these rolls being provided with intermeshing gears 42 and 43, respectively. The gear 42 of each pair of rolls engages with teeth 44 formed on the upper bearing-ring 26; so that as the 105 hood member rotates with respect to the stationary bearing-ring the auxiliary rolls are caused to rotate with respect to each

other but in opposite directions. Chute plates 45 are provided above each pair of auxiliary rolls, so as to deflect any material which may fall onto said plates into said auxiliary rolls, thereby permitting such material to be crushed by said rolls and fall beneath the latter. Each of these chute plates is formed of sheet metal bent to the proper downwardly-inclined 10 shape, so as to form an angular part 45^a which closes the inner part of the angle formed by the adjacent radial arms 29^a of the hood member, two shelf parts 45^b, which terminate substantially at the ends of the rollers 40, 41, and a pair of lip portions 45^c which enter the upper part of the space between said rollers.

The machine is provided with an inlet chute 46, through which the material is 20 delivered to the deflector portion 16 of the receiver; and a fan or the like is provided for delivering an air blast through a pipe 47 beneath the machine, an air suction device carrying the crushed product away to 25 a suitable receptacle. Casing members 48 and 49 are provided for inclosing the various parts described above.

In the operation of the machine, the material to be crushed is suitably fed to the 30 chute 46, through which it falls onto the deflector portion 16, being thereby distributed into the channel portion 17 of the receiver. In this channel portion, the material is crushed, during rotation, beneath the spheres 35 35, which latter are pressed down upon the material by the actions of the springs 33. The crushed material is forced out through the space between the disk 19 and the corresponding oppositely rotating member 38. 40 Upon being thus forced out, it is operated upon by the blast of air coming through the apertures 24 from the pipe 47. This blast of air carries the crushed material upward toward the receptacle. Any particles of 45 material which may not have been sufficiently crushed will fall upon the chute plates 45, and be thereby delivered to the auxiliary rolls 41, 42, by which rolls these particles will be further broken up, and will 50 be thereafter carried upward by the current of air.

It will be observed that the machine described above is of an exceedingly simple and rugged construction, and that it provides for a complete and thorough crushing of the material delivered to it. I do not intend to limit myself to the particular form of machine described and shown, as it is but one of several forms in which my invention 55 may be embodied, what I claim as new, and desire to secure by Letters Patent being:

1. A crushing machine comprising a rotary member having an annular trackway therein for receiving the material to be 60 crushed, a crushing device operating in said

trackway, a second rotary member disposed above said first member co-axially therewith and having a portion coöperating with a portion of said first member so as to grind the material between the members after the 70 same has been crushed by said device, and means for rotating said members in opposite directions.

2. A crushing machine comprising a rotary member having an annular trackway 75 therein for receiving the material to be crushed, a plurality of crushing spheres operating in said trackway, a second rotary member disposed above said first member and having a portion coöperating with a 80 portion of said first member so as to grind the material between the members after the same has been crushed by said spheres, and means for rotating the members in opposite directions.

3. A crushing machine comprising a rotary member having an annular trackway 85 therein for receiving the material to be crushed, a plurality of crushing spheres operating in said trackway, means for exerting pressure on said spheres, a second rotary member disposed above said first-named member and having a portion coöperating with a portion of said first member so as to 90 grind the material between the members 95 after the same has been crushed by said spheres, and means for rotating the members in opposite directions.

4. A crushing machine comprising a rotary member having an annular trackway 100 therein for receiving the material to be crushed, and having a downwardly inclined conical grinding portion extending outward from said trackway, a second member rotatably mounted above said first member and 105 having a conical grinding portion coöperating with the grinding portion of said first member, means for exerting pressure on said second member, and means for rotating said members in opposite directions.

5. A crushing machine having an annular trackway therein for receiving the material to be crushed, and having a downwardly inclined conical grinding portion extending outward from said trackway, a second member rotatably mounted above said first member and having a conical grinding portion coöperating with said first-named grinding portion, a crushing device operating in said trackway, means for exerting pressure on 120 said second member, and means for rotating said members in opposite directions.

6. A crushing machine having an annular trackway therein for receiving the material to be crushed, and having a downwardly inclined conical grinding portion extending outward from said trackway, a second member rotatably mounted above said first member and having a conical grinding portion coöperating with said first-named grinding 125 130

portion, means for exerting pressure on said second member, a plurality of spheres operating in said trackway, means for exerting pressure on said spheres, and means for 5 rotating said members in opposite directions.

7. A crushing machine comprising a rotary member having an annular trackway therein for receiving the material to be 10 crushed, and having a downwardly inclined conical grinding portion extending outward from said trackway, a second member rotatably mounted above said first member and having a conical grinding portion coöperating 15 with the grinding portion of said first member, means for exerting pressure on said second member, a crushing device operating in said trackway, means for rotating said members in opposite directions, a 20 hood for connection with an exhaust means,

and supplementary means for crushing any particles falling back from said hood.

8. A crushing machine comprising a pair of superposed grinding members mounted to rotate one upon the other, a casing 25 surrounding said grinding members so as to provide a chamber for the ground particles, a hood above said grinding members for connection with an exhaust means, and supplementary means for crushing any particles 30 falling back from said hood and returning them to said chamber.

In witness whereof, I have hereunto subscribed my name in the presence of two witnesses.

WILLIAM ELLK.
